REFRIGERATING APPARATUS WITH OVERLOAD CONTROL

Francis I. Rataiczak and Harold C. Pearson, Dayton, Ohio, assignors to General Motors Corporation, Detroit, Mich., a corporation of Delaware

Application April 1, 1953, Serial No. 346,242

2 Claims. (Cl. 62—4)

This invention relates to refrigerating apparatus and more particularly to a construction and arrangement for preventing dangerous or excessive head pressures.

When a leak develops in the evaporator of a refrigerating system, minute quantities of moisture-laden air are admitted to the interior of the system and the accumulation of moisture resulting therefrom sometimes causes frost to form in the restrictor so as to completely block the flow of refrigerant from the condenser into the evaporator. When this happens, the compressor will pull in additional quantities of air into the system at a rate which is insufficient to cause overloading of the compressor even though the head pressure becomes excessive. It is an object of this invention to provide a simple arrangement for stopping the compressor before dangerously high head pressures can develop.

More particularly, it is an object of this invention to provide a pressure operated valve which serves to load the compression chamber with a larger volume of high pressure gas so as to stall the compressor and thereby bring into operation the usual motor overload protectors for de-energizing the compressor motor.

It is another object of this invention to provide a safety valve means which will not result in the loss of any of the refrigerant charge when the valve opens.

Further objects and advantages of the present invention will be apparent from the following description, reference being had to the accompanying drawings, wherein in a preferred form of the present invention is clearly shown.

In the drawings:

Figure 1 is a fragmentary vertical sectional view showing a compressor provided with the invention;

Figure 2 is a sectional view taken substantially on line 2—2 of Figure 1;

Figure 3 is a sectional view taken substantially on line 3—3 of Figure 1;

Figure 4 is a fragmentary sectional view on an enlarged scale showing the construction of the relief valve; and,

Figure 5 is an elevational view largely diagrammatic showing a refrigerating system embodying the invention.

For purposes of illustrating the invention, a refrigerating system of the type used in a household refrigerator has been shown whereas certain aspects of the invention are equally applicable to other types of systems.

Referring now to Figure 5 of the drawing wherein there is shown a complete refrigerating system, reference numeral 10 designates a sealed motor-compressor unit which is adapted to discharge compressed refrigerant into a condenser 12 from whence condensed refrigerant is fed to an evaporator 14 through a fixed restrictor 16. The evaporator 14 is intended to designate a conventional evaporator of the type used for refrigerating the frozen food storage compartment in a household refrigerator. A second evaporator 18 is connected in series with the

2

evaporator 14 and is intended to designate a conventional plate type evaporator of the type commonly used in the main food storage compartment.

The refrigerating system is of the well-known type in which the second evaporator 18 is defrosted during each "off" cycle of the compressor. The refrigerant vaporized in the evaporators is returned to the motor-compressor unit 10 through the return line 20 which leads to the compressor inlet port 22 in accordance with standard practice.

10 A thermostat 24 mounted on the plate evaporator 18 is adapted to start and stop the motor-compressor unit by opening and closing the switch 26 located in the main motor circuit. This thermostat is of the well-known type which opens the circuit at approximately 0° F. and closes the circuit at a temperature slightly above freezing. A conventional motor overload protector 30 is provided as shown for interrupting the flow of current to the compressor motor in the event that the compressor motor becomes overloaded. Since thermostatic control switches and overload protector switches of this type are well known in the art, they will not be described in further detail. Reference is hereby made to Clark Patent 2,447,488 for a disclosure of one type of motor overload protector switch which may be used.

15 It has been found that plate type evaporators which are defrosted during each "off" cycle sometimes develop frost blisters adjacent the edges of the plate which eventually increase in size so as to produce a leak in the evaporator. Since the evaporator pressure then falls below atmospheric pressure air will enter the system through the leak. This air will introduce moisture into the system which tends to freeze in the restrictor line 16 leading from the condenser to the evaporator. When 20 this occurs, it is obvious that the flow of refrigerant into the evaporator will completely stop but minute quantities of air will be pulled into the suction side of the compressor and thereby very gradually build up the head pressure in the system. In view of the fact that the amount of air leaking into the system is usually very small, the compressor does not become overloaded even though the head pressure becomes dangerously high.

25 In the system shown for purposes of illustrating the invention, the compressor is a rotary compressor having a main cylinder element 32 mounted between end plates 34 and 36 in accordance with standard practice. As shown in Fig. 2, a divider block 37 separates the inlet port 22 from the conventional outlet port 38. The outlet port 38 connects to the line 40 (see Fig. 5) which 30 leads to a small heat exchanger 42 which serves to remove some of the heat from the fluid discharged from the compressor before returning the compressed fluid to the interior of the motor-compressor housing designated by the reference numeral 44. Reference character 46 designates the usual drive shaft which has an eccentric portion cooperating with the usual impeller 48. A motor rotor 50 is secured to the upper end of the drive shaft 46 and is disposed to operate within the motor stator 52 located in the upper portion of the housing 44 in accordance with conventional practice.

35 A safety valve assembly 60 has been provided in the upper end plate 34 for artificially loading the compressor at excessively high head pressures so as to cause the usual thermal overload protector 30 to come into operation and stop the compressor.

40 As best shown in Figures 1 and 4 of the drawing, the safety valve assembly is mounted in a passage 62 provided in the upper end plate. The upper end 65 of this passage communicates with the interior of the motor-compressor housing 44 into which the compressed refrigerant discharges. The lower end of the passage com-

municates with the compression chamber 64 adjacent the inlet 22 so that upon downward movement of the valve element 63 in response to excessive head pressure, high pressure gas is fed directly into the compression chamber so as to fill the same with this high pressure gas. The motor lacks the necessary power to further compress this high pressure gas with the result that the overload protector 30 comes into operation to stop the compressor before any further increasing in the head pressure may occur.

The valve consists of a plunger 63 which is biased into sealing engagement with the valve seat 66 by means of a coil spring 68. The lower end of the coil spring 68 is held in place by means of the threaded insert 70. The insert 70 is provided with a screw-driver slot 72 which intersects a central gas passage 74 provided in the lower wall of the insert 70. It will be noted that the bottom end of the insert 70 is beveled as indicated at 76. It will also be noted from Figs. 3 and 4 that the insert 70 is primarily located above the cylinder element 32 so as to prevent the insert 70 from striking the impeller 48 in the event that the insert should become loose and start moving downwardly. It will also be noted that one edge of the beveled portion of the insert 70 overlies the compression chamber. By virtue of this arrangement the screw-driver slot 72 connects the central passage 74 with the compression chamber through the clearance provided by the beveled portion 76 irrespective of the setting of the slot 72.

While the form of embodiment of the invention as herein disclosed constitutes a preferred form, it is to be understood that other forms might be adopted as may come within the scope of the claims which follow.

What is claimed is as follows:

1. In a refrigerating system, a compressor having a compression chamber, a condenser, an evaporator, refrigerant flow connections between said compressor, con-

denser and evaporator, an electric motor for operating said compressor, a source of electrical energy, means connecting said motor to said source of electrical energy including a thermal overload responsive switch interrupting the flow of electricity to said motor in response to an overload on said motor, means forming a bypass from the outlet of said compressor to said compression chamber, and a valve in said bypass operable to admit high pressure refrigerant from the outlet of said compressor to said compression chamber so as to overload said compressor in response to excessive outlet pressures.

2. In combination, a housing, a motor-compressor assembly disposed within said housing, means introducing a fluid to be compressed into said compressor, said compressor having an outlet, means directing the fluid discharged through said outlet into said housing, said compressor including means forming a compression chamber having a passage in its one wall connecting the interior of said housing to said compression chamber, and a pressure responsive valve within said passage operable to admit fluid from said housing to said compression chamber in response to a predetermined increase of pressure within said housing.
